[57] ABSTRACT

In a turbomachine, axial flow leakage of motive fluid between rotor blade tips and the inner circumference of the outer casing is sometimes prevented by utilizing an overlapping (labyrinth) seal and shroud assembly between the blade tips and the outer casing. Removal and assembly of the overlapping shroud seal in an annular, non-split outer casing is greatly facilitated by providing a plurality of shroud segments about the blade tip periphery and a radially outer clearance gap between the shroud segments and the outer casing whereby each shroud segment may be moved radially to unlatch the seal and permit axial removal of the seal without disturbing rotor elements.

SHROUD ASSEMBLY

BACKGROUND OF THE INVENTION

This invention relates in general to turbomachines and more particularly to a shroud assembly for a turbomachine of the type having a non-split annular outer casing.

In a turbomachine, the rotor blades are surrounded at their peripheries by a circumferential shroud assembly attached to the outer casing of the turbomachine. The rotor blade tip and the shroud assembly are closely adjacent one another to form a seal which prevents axial leakage of the motive fluid between the blade tips and the outer casing. One type of seal is the so-called labyrinth seal wherein radially extending blade teeth overlap, in the axial direction, radially depending shroud teeth thereby forming an axial seal.

In the prior art, the overlapping (labyrinth) seal was used exclusively in conjunction with a horizontally split outer casing comprising upper and lower casing halves including upper and lower shroud segments. Replacement of the upper segment was accomplished by removal of the upper casing half. Removal of the lower shroud segment required removal of the rotor, the entire process being costly and time-consuming. It has also now become desirable to employ an annular or non-split outer casing. The present invention describes a construction and method for removing an overlapping (labyrinth) type seal and shroud assembly from an outer casing without disturbing the rotor elements.

It is therefore one object of the present invention to provide an overlapping (labyrinth) seal for an annular, non-split outer casing.

It is another object of the present invention to provide a method for removing a shroud assembly from an annular, non-split casing.

Other objects and advantages will become apparent from the following description of one embodiment of the present invention, and the novel features will be particularly pointed out hereinafter in the claims.

SUMMARY OF THE INVENTION

In a turbomachine including a rotor axially disposed within a non-split, annular outer casing, said rotor including a plurality of radially extending blades, each blade formed with a tip portion having at least one seal tooth and said outer casing including an annular recess adjacent said blade tip portions, an improved shroud assembly as hereinafter described. The shroud assembly includes a plurality of arcuate shroud segments disposed in said outer casing annular recess; each shroud segment including a radially depending shroud tooth which overlaps a respective blade tooth in the axial direction forming a labyrinth seal therewith. The annular recess is formed with an annular stop for radially locating said shroud segments relative to said blade tips. Moreover, a clearance gap remains between the radially outward portion of each shroud segment and the radially inward surface of said outer casing annular recess for receiving a spacer plate which bears against each shroud segment. Fastening means are provided for attaching each shroud segment to the outer casing. In assembly and disassembly operations, the spacer plate may be removed from said clearance gap whereby each shroud segment may be moved radially and axially.

BRIEF DESCRIPTION OF THE DRAWINGS

FIG. 1 is a cross section of a turbomachine (lower half removed) disclosing the details of the present invention.

FIG. 2 is an enlarged cross section of a turbine blade and shroud assembly showing details according to the present invention.

DETAILED DESCRIPTION OF THE INVENTION

Referring to the drawings, particularly to FIG. 1, a turbomachine portion 11 includes annular outer casings 13 which may be axially joined at circumferential flanges 13a and 13b. The annular casings may be nozzle casings, exhaust casings, etc., as is well known in the art. The present invention finds its greatest utility in an annular or "non-split" outer casing, that is, a casing having no horizontal joint for assembly and disassembly. However, it will become apparent that the present invention may be applied to a horizontally split outer casing, if so desired.

A rotor 15 is axially disposed within the outer casing and may include a high pressure wheel 17 and also a low pressure wheel 19. Each wheel contains radially extending blades 21 circumferentially mounted about the respective rotor wheels, as is well known in the art.

FIG. 2, in conjunction with FIG. 1, shows a rotor blade 21 mounted within the outer casing 13. Each rotor blade includes a tip portion comprising a plurality of seal teeth 23. The blade seal teeth are disposed to extend radially outward from the blade tip. The blade teeth form one portion of an axially extending labyrinth seal 25.

The remaining portion of the labyrinth seal comprises an annular shroud assembly formed by a plurality of shroud segments 27 (only one shown) disposed radially outwardly of the blade seal teeth, and having radially depending shroud teeth 29 overlapping in the axial direction, the blade seal teeth. Otherwise stated, the shroud seal teeth extend radially inwardly between the radially outwardly extending blade teeth to create an interference in the axial direction. Each shroud segment is arcuate and the seal teeth may take the form of a number of arcuate rows.

The shroud segments are disposed in an annular recess 31 formed in the outer casing. An annular stop means 33 extends axially into the annular recess. The shroud segment is formed with a mating recess 35 which abuts the stop means when the shroud segment is properly seated into the annular recess. The mating recess 35 is elongated to permit radial movement of the shroud segment in the casing annular recess when the mating recess is proximate the stop means. Each shroud segment is also formed with an axial bore 41 therethrough whereas the outer casing also includes an aligned bore 43. A fastener 45 is threaded through the shroud bore and into the outer casing bore for fastening the shroud segment to the outer casing.

Each shroud segment includes a radially outward surface 49 which is spaced from a radially inward surface 51 of the outer casing thereby defining an arcuate clearance 53 for allowing radial displacement of the shroud during assembly and disassembly. After assembly of each shroud, a spacer plate 55 is inserted into the clearance 53 for positioning the shroud segment radially inwardly toward the blade tips.

Having described the construction of the present invention, the operation is as follows. With an adjacent casing removed, individual shroud segments may be inserted into a "non-split" annular turbomachine outer casing to form a labyrinth seal, in the axial direction, with rotor blade seal teeth while the rotor is axially positioned within the outer casing. Each shroud segment is axially inserted within the outer casing annular recess 31 until contact is made between the shroud segment and the rear wall of the annular recess defined by a depending portion of the outer casing as shown. Each shroud segment is held radially outward in the clearance 53 until the proper circumferential position as heretofore defined is achieved. Thereafter, each shroud segment is moved radially inward until annular stop 33 is contacted and the respective blade and shroud teeth are disposed in an axially overlapping position. Fasteners 45 are then inserted into bores 41 and 43 in the shroud segment and outer casing respectively. This assembly is the reverse of the aforementioned procedure whereby the shroud segment is moved radially outward to unlatch the blade and shroud teeth and then axially removed. Thus, in an annular non-split outer casing shroud segments may be assembled and removed without disturbing the rotor blades.

While a specific embodiment of the invention has been shown, it will be obvious to those skilled in the art that changes and modifications may be made without departing from the invention. It is therefore intended in the appended claims to cover all such changes and modifications that fall within the true spirit and scope of the invention.

What is claimed is:

1. In a turbomachine, including a rotor axially disposed within a unitary outer casing, said rotor formed with a plurality of radially extending rotor blades, each blade having at least one radially extending seal tooth; and, said outer casing being formed with an open end annular recess circumferentially adjacent said rotor blades seal teeth; a shroud assembly comprising:
35 a plurality of shroud segments disposed in said open end annular recess;
40 at least one shroud seal tooth radially dependent

- from each shroud segment and overlapping a blade seal tooth in the axial direction to form an axial seal therewith; and,
5 a clearance defined between a radially outer surface of each shroud segment and a radially inner surface of said outer casing whereby each shroud segment may be moved radially outward to unlatch respective blade and shroud teeth prior to axial removal from the outer casing;
10 an annular stop formed on said outer casing extending axially into said annular recess; and,
a recess formed in each shroud segment for engaging a portion of said annular stop.
15 2. The shroud assembly recited in claim 1 wherein said recess formed in the shroud segment is elongated in the radial direction to allow radial positioning of the shroud segment when the shroud segment recess is proximate to the annular stop.
20 3. In a turbomachine a rotor axially disposed within an annular, non-split outer casing, said rotor formed with a plurality of radially extending rotor blades, each blade having radially extending seal teeth, and, said outer casing having an open end annular recess circumferentially adjacent said rotor blade seal teeth; a shroud assembly comprising:
25 a plurality of shroud segments disposed in said open end annular recess; each shroud segment including a plurality of radially depending shroud seal teeth which overlap said radially extending blade seal teeth in the axial direction forming an axial labyrinth seal therewith;
30 a clearance defined between a radially outer surface of each shroud segment and a radially inner surface of said outer casing;
a spacer plate removably positioned in said clearance between each shroud segment and the outer casing; an annular stop formed on said outer casing extending axially into said annular recess;
35 a recess formed in each shroud segment for engaging a portion of said annular stop; and,
40 fastening means for attaching each shroud segment to the outer casing.
